UNITED STATES PATENT OFFICE.

MELCHIOR ZWICKY, OF BERKSHIRE HEIGHTS, PENNSYLVANIA, ASSIGNOR TO TEXTILE MACHINE WORKS, OF WYOMISSING, PENNSYLVANIA, A CORPORATION OF PENNSYLVANIA.

SLACK-PREVENTING GUIDE DEVICE FOR KNITTING MACHINES.

Application filed November 23, 1927. Serial No. 235,318.

This invention relates to a yarn feed mechanism for knitting machines, and more particularly to a thread guide device comprising a frame having an eyeleted guide eye passing through a thread-supporting shelf upon which latter a flat spring normally rests to press upon the passing thread, said spring being raised to free the thread during feeding movement of the latter but engaging the same 10 at times to prevent slack thereof.

Such devices are in common use and are usually known as "snappers", and as heretofore made have been the source of much trouble and annoyance due to the friction of the 15 thread cutting grooves in their supporting shelf, to the harm of the latter and the thread, and such grooves destroying proper contact of the spring in its slack preventing pressure on the thread.

20 The object of the present invention is to avoid such harmful thread cutting of the supporting shelf, prolong indefinitely the useful life of the device, and do away with the constant need of care and adjustment to insure 25 desired prevention of slack thread; and, with this end in view, it comprises the improved construction hereinafter fully described in connection with the accompanying drawings, the novel features of which are set forth in 30 the appended claim.

Fig. 1 shows in plan view a thread guide device or snapper embodying my improvements, such views showing its usual rotated supporting shaft and spring lifting rod.

35 Fig. 2 is a side elevation corresponding with Fig. 1 but indicating also the machine frame support for the rotated shaft and spring lifting rod.

Thread guide devices or snappers such as 40 illustrated in the drawings, are particularly applicable to full fashioned knitting machines, a series of them corresponding with the number of threads in the several machine sections, being employed and commonly 45 secured to one or more supporting shafts 5 extending longitudinally of the machine above the knitting sections and usually rotatably mounted in machine frame members 6; partial rotation of said shaft being effected as 50 heretofore from the knitting machine cam shaft in well known manner through a push rod 7 connected to an arm 8 fixed to said shaft as indicated.

Each guide device or snapper thus em-

ployed, as heretofore, and as illustrated in the 55 drawings, comprises a shaft-engaging portion 10, preferably open for lateral placement and removal on the shaft, and held in fixed position on the latter by a set screw 11, said portion 10 having diverging extensions 12 and 60 13, the outer end of the latter forming a seat to which one end of a flat spring 14 is secured, as by screws 15, and the former, 12, having a thread-supporting shelf 16 upon which the 65 spring 14 rests in flat position and extends 17 therebeyond, covering a thread-guide eye 18 formed in said shelf 16, which eye is angularly disposed to a thread-guide eye 19 formed in extension 13. The thread 19 passing through eye 18, over shelf 16, and through eye 70 17 is held to said shelf by pressure of spring 14, except when the latter is lifted by the turning of shaft 5, when the free end of said spring contacts with a fixed rod 20 extending in 75 spaced parallel relation to shaft 5. The shaft 5 may of course be fixed and the rod 20 moved to lift the spring.

The construction thus far described is old and well known, but as commonly made, preferably of cast iron for cheapness, it has inherent defects causing trouble and annoyance besides the expense of repairing or replacing. The friction of the passing thread 19, particularly where silk or artificial silk is employed, soon causes a groove to be worn in the 85 surface of the thread supporting shelf 16 into which the thread sinks so that the spring 14 does not properly press upon the same to prevent slack; and such groove cutting is not only hurtful to the thread, but when cut is 90 likely to catch slight harmless thickened portions of the latter and cause breakage thereof.

To overcome the above inherent defects while continuing the use of the cheaply formed iron castings, the present improvements consist in employing a porcelain eyelet in thread guide aperture 17 as heretofore, but forming the same of such length as to project and extend above the surface of the thread-supporting shelf 16, so that the thread 19, 100 when tautened as during its feeding movement, will be lifted free of contact with shelf 16 as it is drawn over the upper lip 21 of the extended eyelet, but which when not feeding or slackened, may be pressed against such 105 shelf as heretofore; the spring 14 being provided with an enlarged opening or aperture 22 through which the projecting end 21 of

eyelet 17 freely extends. Such opening does not affect the action of the spring in pressing the thread against shelf 16, and the thread cannot cause cutting of the shelf surface as such thread is not moving when the spring is in slack preventing contact with it. The hard porcelain lip 21 of the upwardly projecting eyelet provides a smooth wear-resisting contact for the feeding yarn which indefinitely insures against any wearing contact with the shelf.

From the foregoing description it is thought that the nature of the invention and its operation will be readily understood; and the improvements, though simple and readily made, are important as avoiding in a cheap and effective way the inherent defects of such thread guide devices or snappers as heretofore made, while

permitting their continued manufacture of simple iron castings which is particularly desirable.

What I claim is:

In a yarn feed mechanism for knitting machines, a thread-guide device comprising a frame having a spring-carrying arm provided with a guide-eye, and a thread-supporting shelf having a guide eye with an upwardly projecting eyelet therein; a flat spring fitted to said arm, and having its free end apertured for passage of said projecting eyelet and adapted to normally press the thread into contact with said shelf; and means for raising the free end of said spring to permit free feeding of the eyelet-raised thread.

In testimony whereof I affix my signature.
MELCHIOR ZWICKY.
